UNITED STATES PATENT OFFICE.

PRESTON H. ALLEN AND HENRY H. ALLEN, OF ST. LOUIS, MISSOURI, ASSIGNORS TO BEMIS BRO. BAG COMPANY, OF ST. LOUIS, MISSOURI, A CORPORATION OF MISSOURI.

WATERPROOF CONTAINER OR ENVELOP.

1,295,832.

Specification of Letters Patent.

Patented Mar. 4, 1919.

Application filed May 7, 1918. Serial No. 233,128.

To all whom it may concern:

Be it known that we, PRESTON H. ALLEN and HENRY H. ALLEN, citizens of the United States, and residents, respectively, of St.

5 Louis, Missouri, have invented certain new and useful Improvements in Waterproof Containers or Envelops, of which the following is a specification containing a full, clear, and exact description, reference being 10 had to the accompanying drawings, forming a part hereof.

Our invention relates to certain new and useful Improvements in "waterproof containers or envelops" and has for its special 15 object the construction of a container or envelop made out of waterproof material, and so constructed that the mouth of the container or its open end may be closed and made practically waterproof by the folding 20 of the material out of which the container is made.

Furthermore our invention has for one of its special objects a fastening device for the container which is firmly united to the container and is proof against the entrance of 25 water to the container, or dust, etc.

In the drawings,

Figure 1 is an inside view of the blank out of which our container is formed. 30 Fig. 2 is a plan view of the container illustrating the closing flap unfolded.

Fig. 3 is a plan view of the container with the closing flap completely formed and folded.

35 Fig. 4 is a plan view of the container closed.

Fig. 5 is an enlarged sectional view illustrating the material out of which the container is formed, and

40 Fig. 6 is a section taken on a line 6—6 of Fig. 4.

Referring to the drawings, 7 indicates the blank out of which the container or envelop is formed, which is composed of two sheets of 45 flexible fabric or material 8, between which there is a coating or sheet of waterproof material 9. In practice the material out of which our container or envelop is made is two sheets of paper between

50 which there is a coating of waterproof adhesive material. In the making of our container the material out of which it is made is cut and scored, perforated or punched, as illustrated in Fig. 1, wherein 10 indicates 55 the score line on which the material is folded

and which constitutes the bottom closed end of the container or envelop, that is, when the portion 11 is folded on the portion 7^a along the line 10.

Secured to the portion 11 is a fastener 60 which has an inner disk 12 and an outer disk 13. These disks 12 and 13 are connected together by a metal sleeve 14, and between which the material out of which the container is formed is located. 65

The metal sleeve or eyelet 14 has a flange on its outside, and its inner edge is folded over or upset so that the two disks 12 and 13 are firmly united over the material out of which the container is formed. 70

After the blank 7 has been folded along the line 10 the two portions 7^a and 11 are sewed together by means of stitching 15 and 16, the stitching continuing throughout the flap 17. 75

The flap 17 is then folded along the line 18 and the companion fastener 19 is secured to the flap.

In Fig. 2 we have illustrated the flap 17 unfolded and in Fig. 3 we have shown the flap folded along the folding line 18 and the flap secured in its folded position by means of the fastener 19. The sleeve of the fastener 19 is inserted through the openings 20 and 21 of the flap which coincide when the flap is folded and which has a thin disk 22 and a slightly heavier disk 23. These disks are united by means of the metal eyelet 24. The fastener 19 is further provided with a fastening cord 25 and a wire fastener 26. When the fastener 19 has been secured to the folded flap as described and illustrated in Fig. 3 the container or envelop is then ready for use and in order to close the container the folded flap as illustrated in Fig. 3 is then folded down on the folding line 26' and upon the container body. When the flap has been folded along the line 26' it will be understood that a portion of the flap will also be folded upon itself along the line 28 thus forming a flap 29 which, when the container has been closed will lie over the edge 28' of the container. 95

In the construction and operation of closing the container it will be observed that the flap 17 is first folded upon itself along the line 18 and is then of two thicknesses of material and is secured together by the fastener 19, and this folded flap, as it were, is provided with the flap portion 29 which 110

occupies the position between the folded flap and the body of the container when it has been closed, as illustrated in Figs. 4 and 6.

5 It will be seen therefore that the closing is effected by the flap 29 which lies adjacent and over the top edge 28' of the container.

This flap 29 between the container body and the folded flap when the folded flap is 10 secured in position exerts a slightly yielding or springing pressure over and against the top edge 28' of the container.

The container is closed by means of passing the cord 25 around the fastener secured 15 to the body of the container in the usual way.

In Fig. 4 we have shown the container closed and sealed by means of a seal 31.

It will be observed from examination of 20 Fig. 2 that the score line 26' is arranged slightly above the top edge 28' of the container and that the score line 26' and 28 practically coincide when the flap is folded and that when the mouth of the container 25 is closed the flap 29 overlies the top edge 28' of the mouth of the container. The flap 29 as previously stated is carried by the folded flap or that portion of the same that extends below the fastener and it is yieldingly mounted on the folded flap so that 30 when the container is closed, said flap 29 exerts a constant yielding pressure over and along the top edge 28' of the mouth of the container.

35 Having fully described our invention, what we claim is:

1. A container or envelop constructed of

water-proof material and stitched along its sides to close the sides of the container, a folded flap projecting beyond the mouth of 40 the container, said folded flap being held in a folded condition by means of a fastener passing through the folds thereof near the folding line, a flap carried by the folded flap and adapted to lie between the folded flap and container and over the edge of the latter when the folded flap has been closed, a fastener secured to the body of the container, and means for connecting said fasteners. 45

50 2. A container or envelop constructed of water-proof material and stitched along its sides to close the sides of the container, a folded flap projecting beyond the mouth of the container, and adapted to be folded along 55 a line slightly removed from the mouth of the container, said folded flap being held in a folded position by means of a fastener passing through the folds thereof near the line on which the folded flap is folded, a flap 60 carried by the free end of the folded flap and adapted to lie over the edge of the container when the folded flap has been closed, a fastener secured to the body of the container, and means for connecting said fasteners. 65

In testimony whereof, we have signed our names to this specification, in presence of two subscribing witnesses.

PRESTON H. ALLEN.
HENRY H. ALLEN.
